Louis Fischer

United States Patent Office.

LOUIS FISCHER, OF BROOKLYN, NEW YORK.

Letters Patent No. 91,533, dated June 22, 1869.

IMPROVEMENT IN VAPOR-BURNERS.

The Schedule referred to in these Letters Patent and making part of the same.

To all whom it may concern:

Be it known that I, LOUIS FISCHER, of the city of Brooklyn, in the county of Kings, and State of New York, have made certain new and useful Improvements in Vapor-Burners; and I do hereby declare that the following is a full, clear, and exact description of the same, reference being had to the accompanying drawings, and letters of reference marked thereon, making part of this specification, in which—

Figure 1 represents a side elevation of a burner, with my improvements.

Figure 2 is a vertical central section of the burner-tube and burner of the same.

Figure 3 is a longitudinal section of the wick-tube, insulator, and supply-pipe of the same, shown on an enlarged scale.

Similar letters of reference indicate corresponding parts in the several figures.

The nature of this invention consists in providing a wire-screen, or perforated guards, to be employed on the air-passages of the burner-tube, so as to divide the current of air when coming in contact with the vapor, whereby the usual noise made in using the burner is most effectually stopped, and the vapors are protected against condensation by cold or strong currents of air, and also against vibration, and the disturbance of their properly mixing and passing to the burner.

To enable others skilled in the art to make and use my improvements, I will proceed to describe their construction and operation.

A represents the ordinary supply-tube leading to the oil, from the basin to the wick.

B is the insulator, combining the wick-tube with the supply-pipe; and

C, the retort in which the gas is generated.

D is the burner-tube, provided with the air-passages E E, and furnished with the usual valve F, and valve-passages G.

I provide the top end of the burner-tube with a round burner-tip, H, as shown, having passages h h through its cross-piece i, leading from the main passage I of the burner-tube.

Now, in order to stop the usual noise in operating these burners, I employ a perforated guard, or wire screen, K, over the air-passages E, which may be secured in any convenient manner, and instead of wire, the screen, or guards may be constructed of other perforated or porous substances, in any suitable manner, so as to divide the current of air passing through the said passages.

In the ordinary vapor-burner, the wick-tube forms

part of the supply-pipe, the end of which is directly connected with the rear part of the retort, and when a new one is to be placed in it, the old one is removed by detaching the retort from said pipe, at their junction.

In using the burner, after a short time the wick becomes burned, and in that case the end of the retort becomes frequently immovable, so that it is very difficult to remove the wick and replace it by another without destroying the supply-pipe by the operation.

Now, in order to facilitate the removing of the said wick, I arrange the supply-pipe with a junction, at a distance of several inches from its junction with the retort, and use that part for replacing the wick. I make this junction with a union-coupling, provided so as to insulate the heat from the retort and wick-tube from the supply-pipe, which consists in constructing the end of the supply-pipe with the shoulder L, having a screw-thread on its periphery, over which is fitted a coupling-nut, M; and in constructing the corresponding end of the wick-tube with the shoulder N loosely fitting the inside diameter of the nut M, and having one, two, or more washers, O O, of pasteboard or other insulating-material employed between the faces of the joining ends of the said pipes, while having a similar washer, P, employed on the rear face of the shoulder N; and between it and the inside shoulder Q of the nut M, I employ a metal washer, to protect the washer W from being torn or otherwise damaged in tightening the nut M.

By these means, the supply-pipe is insulated from the wick-tube very effectively, so that very little heat is conducted to it, and that a proper, easily-operating, and detachable connection is obtained between the supply and wick-tube, so that the wick of the burner may be withdrawn and replaced with more facility than with those heretofore in use.

I am aware that a gate has been employed to regulate the quantity of air passing through the air-passages, as seen in Letters Patent granted to D. H. Carpenter, August 4, 1857, whose invention I hereby disclaim; but

What I do claim as my invention, and desire to secure by Letters Patent, is—

The screen, or perforated guard K, in combination with the air-passages F F, when employed on vapor-burners, substantially as and for the purpose herein set forth.

LOUIS FISCHER.
